UNITED STATES PATENT OFFICE.

JAMES G. BRYANT, OF PORT HURON, MICHIGAN.

ATTRITION MILL.

Application filed March 22, 1926. Serial No. 86,504.

The present invention relates to attrition mills and particularly to mills for coarse and fine grinding or crushing such materials as ear corn.

Among the objects of the invention is an attrition mill unit crusher and grinder which may be more economically produced and efficiently operated than heretofore.

Another object is a disc mill and preliminary crusher in tandem and so constructed and arranged as to be maintained in proper relation and adjustment with the least possible attention.

With these and other objects in view as will be readily apparent to those skilled in the art the invention consists in the construction and arrangement indicated in the accompanying drawings together with any modifications and variations thereof as may come within 20 the scope of the hereunto appended claims.

In the drawings:

Fig. 1 is a longitudinal vertical section through a mill embodying the invention.

Fig. 2 is a section on the line 2—2 of Fig. 1.
25 Fig. 3 is an end view from the left of Fig. 1, of the base member.

Fig. 4 is a view similar to Fig. 2 of a modified form.

As shown, the mill embodying the preferred form of the invention consists of a base member 10 acting as a cradle like support for a hopper 11. The latter is provided with longitudinal horizontal flanges 12 adapted to rest upon the edges of base 10 while the 30 rounded bottom of hopper 11 rests in the cut away part 13 of the base, the whole constituting the supporting frame for the other elements of the mill.

In the form shown in Fig. 4, the base 10 is 40 omitted and the flanges 12 extended downwardly to form the supporting members 12^a, producing a one piece frame for the mill.

The hopper member 11 is provided with substantially vertical sides and its bottom portion is formed as though part of a truncated cone whose axis is horizontal. The ends 15 and 16 of hopper 11 are vertical and provided with circular openings 15^a and 16^a, concentric with and perpendicular to the axis of the conical bottom. The end 15 is machined to provide a proper seat for a bearing housing 17 in which is located a suitable bearing 18 for shaft 19. The latter extends beyond the housing 17 and has 55 secured to it the drive pulley 20, the housing being closed around the shaft by a suitable

closure member 21. The inner end of housing 17 is preferably closed around the shaft by a suitable wall or diaphragm 22 to prevent passage of oil or materials being ground.

End wall 16 is provided with two seats concentric with and perpendicular to the axis of the conical portion of the hopper. To the outer seat is secured the housing 30 and to the inner seat is secured the ring shaped cutter 31. 60 This housing 30 serves to house the cutters and provides a support for the shaft bearing at this end of the machine. The outer face is provided with an opening 32 concentric with the axis of the hopper bottom and is faced 70 around said opening to seat a second bearing housing 33 containing bearing 34 for the other end of shaft 19. The inner end of housing 33 is closed around the shaft as at 35 and the outer end of the housing is provided with a thrust bearing 36 having means 75 for adjustment such as the screw 37.

Housing 30 is open at the bottom as at 40 to provide for escape of ground materials.

Mounted in the aligned bearings 18 and 34 80 as stated is the shaft 19 and mounted on the shaft within the hopper 11 is a conical crushing element or breaking cone 45 provided with teeth 46 adapted to coat with a breaking bar 47 lying longitudinally in the bottom of 85 the hopper. These elements serve for coarse crushing or grinding. A single initial breaker 48 may be used to break into smaller fragments large pieces of material such as whole ears of corn so that they more readily get 90 under the breaking cone.

Also mounted on shaft 19 is a gridding disc 50. This may form a supporting end for the breaking cone 45 as shown and is provided with a cutter ring 51 about the periphery of 95 the face adjacent the hopper which ring 51 coacts with ring 31 for finely grinding or cutting the coarse material from hopper 11.

In operation, the cone 45 serves both as a coarse grinder and as a feed to the disc 100 grinder and both may be adjusted by means of the screw 37.

It should be noted that the seats for the bearing housing 18, the housing 30 and the cutter 31 are all machined on the single frame 105 or hopper member 11 and that all are concentric with and in planes perpendicular to the same axis, which is the axis of the shaft 19. Further, the bearing housing 33 is seated on housing 30 on a similarly placed seat, so that 110 with the disc 50 carrying cutter 51 properly mounted in a plane perpendicular to the axis

of shaft 19, assembly of the several parts automatically takes care of the alignment of parts and parallelism of the cutters.

By reason of the construction described including the adjustment, the device is suitable for reducing a variety of materials in addition to the ear corn mentioned.

Now having described the invention and the preferred forms of embodiment thereof it is to be understood that the said invention is not to be limited to the precise details herein described and illustrated but only by the scope of the claims which follow.

Claims:

- 15 1. An attrition mill consisting of a frame portion having substantially vertical end walls, aligned bearings supported upon said walls, a shaft supported in said bearings, an attrition element carried by said shaft and adapted to cooperate with another attrition element fixed to said frame portion and a separate pedestal for supporting said frame and parts carried thereby.
- 20 2. An attrition mill consisting of a frame portion having parallel end walls, aligned bearings supported upon said walls, a shaft supported in said bearings, an attrition element carried by said shaft in a plane perpendicular to the axis of said shaft, a coating attrition element carried by one of said walls, the seats for said bearings and said latter element being parallel with each other and concentric with and perpendicular to the axis of the shaft and a separate pedestal for supporting said frame and parts carried thereby.
- 25 3. An attrition mill comprising a hopper portion, having a rounded bottom and vertical end walls, a shaft passing through said end walls, a bearing for said shaft carried

by one of said walls, a housing carried by the other of said walls said housing supporting a second bearing for the shaft, the bearings being in alignment and concentric with said rounded bottom, attrition elements within said hopper and other attrition elements within said housing but outside of said hopper.

4. An attrition mill comprising a hopper having vertical end walls, a crushing element within said hopper, a grinding element carried on the outside of one of said end walls, a shaft traversing said hopper, said shaft carrying a breaking cone within said hopper and a grinding element outside of said hopper but adapted to cooperate with the first grinding element, aligned bearings for said shaft supported by said hopper and a separate supporting element for said hopper and parts carried thereby.

5. An attrition mill comprising a frame member also constituting a hopper, vertical end walls therefor having parallel seats machined on their outer surfaces, circular openings in said end walls concentric with said seats, a bearing housing secured to the seat on one end, an attrition element secured to one of the seats on the other end, a housing seated on another of said seats on the latter end, said housing having an opening in alignment with the openings in said frame member and also having machined on its outer face a seat parallel with the other seats, a bearing housing secured to the last mentioned seat, a shaft carrying an attrition element, adapted to coact with the above mentioned element, mounted in bearings in said housings, and a supporting member for said frame member.

JAMES G. BRYANT.
